UNITED STATES PATENT OFFICE.

FRANK M. LEAVITT, OF SMITHTOWN, NEW YORK, ASSIGNOR TO E. W. BLISS COMPANY, OF BROOKLYN, NEW YORK, A CORPORATION OF WEST VIRGINIA.

IGNITION DEVICE.

1,088,911.

Specification of Letters Patent.

Patented Mar. 3, 1914.

Application filed May 29, 1913. Serial No. 770,740.

To all whom it may concern:

Be it known that I, FRANK M. LEAVITT, a citizen of the United States, residing in Smithtown, in the county of Suffolk and State of New York, have invented certain new and useful Improvements in Ignition Devices, of which the following is a specification.

This invention provides an igniter especially designed for igniting the fuel in a heater (or so-called "superheater") for automobile torpedoes. In such torpedoes it is customary to pass the compressed air on its way from the reducing valve to the turbine or other engine through a heater-pot, in which it is heated by the flame from burning alcohol or other liquid or gaseous fuel, the products of combustion from which are added to the supply of air, thereby greatly increasing the energy of the torpedo.

In the ignition device or fuse heretofore used a pencil of smokeless powder or cordite was suspended in the heating pot from a suitable holder engaging the upper end of the pencil, and by means of an ordinary blank cartridge the upper end of such pencil was ignited. This pencil would frequently burn off from its support at its upper end, and leave an unconsumed portion of the pencil in solid form, which was apt to fall off and pass into the turbine, which it was liable to damage. In order to retain the powder while burning, the pencil was surrounded by a steel tube having openings for the powder gases and flame to escape to ignite the surrounding gaseous or vaporized fuel. The heat in the heater-pot, however, is so great, that the steel holder is liable to fuse off after a few runs, and the molten metal from such holder will clog the turbine.

The object of the present invention is to overcome the difficulties above referred to, and to provide an ignition device peculiarly adapted for use in igniting the charge used to heat and augment the pressure of the propelling fluid in submarine torpedoes, and one wherein complete combustion of the fuse, particularly a slow-burning fuse, is had, and to effect the combustion of the fuse in such manner as to safeguard the surrounding portions of the apparatus, and to pre-

vent the passage to the operative parts of unconsumed portions of the fuse and fused portions of the apparatus.

In the drawing accompanying this specification one practicable embodiment of the invention is illustrated in central longitudinal section applied to a form of heater pot, which is shown partly in elevation and partly in longitudinal section.

The heater pot shown by way of illustration is designated by the reference character 1. To this heater pot is secured a suitable head 2 which has a coupling 3 for connection with the air supply, and an outlet 4 leading to the turbine nozzle. This outlet in the present illustration is shown at the bottom of the heater.

A plug 5 is shown mounted in the head 2. This plug constitutes a chamber for receiving the blank cartridge 6 and a holder for the fuse 7, such fuse being shown in the form of a pencil, which will be made of some comparatively slow-burning material, such, for instance as cordite. This pencil in the illustration is supported in a vertical position, being dependent from the holder 5 and having its free end extending into the heater pot 1. In the present showing the end of the holder barely extends beyond the baffle plate 17.

There is shown inclosing the fuse pencil 7 a casing 8 which has screw-threaded connection at its upper end with the lower end of the holder 5, and affords a chamber or space 9 about the pencil. The casing is provided at its lower ends with openings 10. The lower part of the plug or holder 5 is chambered at 11 for receiving the flash or flame from the cartridge when this is exploded. Suitable passages 12 for the flame extend from the chamber 11 into the chamber 9. The cartridge is exploded in the present illustration by means of a hammer 13, which is actuated in a well known manner by a portion of the compressed air finding access to its upper end through the conduit 14. The outlet or vent from the chamber 9, being provided at 10 adjacent the free end of the pencil 7, will tend to induce the ignition of the pencil at its free end, so that the combustion of the pencil will be substantially complete. But, to as-

sure the ignition at this point and to assure instantaneous ignition, and to cause the pencil to ignite first at its lower end and to burn mainly backward to its point of support, some readily combustible end quick-burning material 15 will be provided in the end of the casing 8 at the free end of such pencil. For instance, a mass of gun-cotton 15 will be placed at this position so that, 10 upon the passage of the flame into the chamber 9, it will immediately ignite and will itself ignite the free end of the pencil.

The casing 8 is shown open at its free end, such opening being closed by some closure which will be of a combustible nature and which may be readily blown out by the discharge from the cartridge 6. This closure in the present instance is shown as a paper cap 16, which holds the mass of gun-cotton 15 in position. The cap is preferably made of a paper which is impervious to moisture so as to assure the dryness of the gun-cotton. To further safeguard the gun-cotton and the fuse 7, the openings 10 15 are also covered with paper 18 impervious to moisture. The paper, upon the flash entering the chamber 9, will either be consumed or blown off.

To safeguard the machinery, for instance 30 the turbine, from being clogged by fused portions of the apparatus finding access to it, the casing 8 is made of some inflammable material, for instance, celluloid, so that upon the ignition of the mass 15 not only 35 will the pencil 7 be ignited, but the casing also will be ignited and will burn rapidly, but not as rapidly as does the fuse pencil 7. This will also add to the heat produced within the heating pot 1 and will also effect 40 the desired result in that a material which is completely combustible is employed for this casing. Celluloid being impervious to moisture, will prevent any moisture getting to the inflammable parts within it.

45 Although but one embodiment of the invention is shown, it will be understood that this is illustrative of the improvement, and that changes may be made within the scope

of the claims without departing from the spirit of the invention. 50

I claim as my invention:—

1. An ignition device comprising a slow-burning fuse supported at one end, and a casing of inflammable material so arranged that when the primer is detonated the flame 55 therefrom will pass between the fuse and the casing and ignite the former at its free end.

2. An ignition device comprising a cor-dite pencil supported at one end, and a cel-luloid casing surrounding such pencil.

3. In an ignition device, the combination with an elongated body of slow-burning material, of a holder engaging one end of such body, an inflammable casing surrounding such body, a mass of inflammable material in the casing at the free end of the said body, and means for passing a flame through the casing to such mass. 65

4. The combination with a slow-burning 70 fuse, of a holder from which the fuse is pendant, and a casing inclosing the fuse having a flame opening at one end, and a vent hole at its other end.

5. The combination with a holder, of a 75 pencil of inflammable material supported at one end by the holder, an inflammable casing supported by the holder and surrounding the pencil, said casing being provided at its other end with an opening, and a 80 readily rupturable covering for said opening.

6. The combination with a heating pot for a submarine turbine, and a baffle plate located in the upper portion of such pot, of 85 a holder located above such baffle plate and extending partially through the same, and a fuse and inflammable casing therefor dependent from such holder.

In witness whereof, I have hereunto 90 signed my name in the presence of two subscribing witnesses.

FRANK M. LEAVITT.
